UNITED STATES PATENT OFFICE

144,476

DESIGN FOR A COMBINED DISPENSING AND ARTICLE DISPLAY CABINET

Albert E. Aldridge, Elkins Park, Pa., assignor to Sun Oil Company, Philadelphia, Pa., a corporation of New Jersey

Application March 30, 1945, Serial No. 118,791

Term of patent 14 years

(Cl. D52—2)

To all whom it may concern:

Be it known that I, Albert E. Aldridge, a citizen of the United States, residing in Elkins Park, county of Montgomery, Commonwealth of Pennsylvania, have invented a new, original, and ornamental Design for Combined Dispensing and Article Display Cabinet, of which the following is a specification, reference being had to the accompanying drawing, which forms a part thereof.

The figure is a front perspective view of a combined dispensing and article display cabinet embodying my new design.

The dominant features of the design reside in the portions shown in full lines.

The opposite side of the cabinet is similar in appearance to the side shown.

I claim:

The ornamental design for a combined dispensing and article display cabinet as shown and described.

ALBERT E. ALDRIDGE.
